D. Anthony Claine
Attorney.

UNITED STATES PATENT OFFICE.

HENRY C. STIFF, OF JOHNSTOWN, PENNSYLVANIA.

SWITCH CONSTRUCTION.

1,299,806.

Specification of Letters Patent. Patented Apr. 8, 1919.

Application filed January 3, 1919. Serial No. 269,453.

To all whom it may concern:

Be it known that I, HENRY C. STIFF, a citizen of the United States, and resident of Johnstown, in the county of Cambria and State of Pennsylvania, have invented certain new and useful Improvements in Switch Constructions, of which the following is a specification.

My invention relates to the construction of tongue switches and is designed to provide a T-rail tongue switch of simple and durable construction having improved means whereby the swinging switch tongue is fastened in place in the switch structure.

One object of the invention is the provision of a switch structure having novel means whereby the switch tongue is secured in place within the pocket of the body or bed of the switch and tilting or lifting movement of the tongue in the pocket is avoided and overcome without interference with the sidewise swinging movements of the switch tongue.

With this and other objects in view, the invention consists in the novel construction, arrangement and combination of parts, all substantially as hereinafter described, and pointed out in the appended claims, reference being had to the accompanying drawings forming part of this specification, in which—

Figure 1 is a plan showing a tongue switch of the T-rail type embodying the novel features of my invention.

Figs. 2 and 3 are transverse sections on the lines II—II and III—III, respectively, of Fig. 1.

Fig. 4 is a sectional side elevation showing details in the construction of the switch tongue fastening forming part of the switches embodying my invention.

Fig. 5 is a horizontal section on the line V—V of Fig. 4 showing details in the construction of the switch tongue.

Fig. 6 is a plan and Fig. 7 an end elevation of the cover or lid for the box at the side of the switch structure.

In the accompanying drawings the numeral 2 designates the body or bed of the switch structure having a shallow depression or recess in its upper horizontal face forming a pocket 3 in which the sidewise swinging tongue 4 of the switch is operatively positioned.

The side surfaces of the body 2 are made to fit the contour outlined by the sloping

under surface of the head, sloping upper surface of the bottom flange and the web of the T-rails 5 and 6 forming part of the switch structure. The rails 5 and 6 are bent so as to bulge outwardly at a point adjacent to the point of the switch tongue to provide space for the manganese steel insert 7, forming part of the switch structure, and the parts are rigidly fastened together by the series of through bolts 8 and 9 in the usual and well known manner. The rear end or heel 10 of the switch tongue has an integral projection or pin 11 on its lower face which projects downwardly into an axially vertical hole in the bottom of the pocket 3, this hole extending through the integral boss 12 on the lower side of the bed 2 so as to form a bearing for the pin 11, as is best shown in Fig. 4.

The bed 2 also is provided with a hole 13 which extends from the upper surface of the bottom of the pocket 3 to the lower face of the switch body, this hole 13 being somewhat larger than the integrally formed lug 14 or ear 14 on the lower surface of the switch tongue 4 which extends downwardly thereto. The lug 14 has a transverse opening 15 therein of peculiar construction, this hole being cylindrical in outline at the middle of its length in both a vertical and a horizontal plane and being elliptical or oval in outline at the side surfaces of the lug 14 in a horizontal plane. (See Figs. 1, 4, and 5). The switch bed 2 has holes 16, 16 therein in which register with the flaring opening 15 in the lug 14 of the switch tongue, and extending through the openings 15 and 16 is a cylindrical bolt or pin 17 by which the switch tongue 4 is fastened in place within the pocket 3 of the switch body. It will be seen by reference to Fig. 1 that the pin 17 is located on the tongue at a short distance in advance of the vertical axis of the heel 10 of the tongue 4, so that the tongue, which, in the operation of the switch, swings from side to side of the pocket 3, is securely held in place and is prevented from lifting bodily or tilting within the pocket 3. The peculiar shape of the opening 15 in the lug 14 provides the clearance required to permit of the necessary sidewise swinging movement of the switch tongue when the switch is in use without the occurrence of binding between the surfaces of the opening 15 and 110 bolt or pin 17.

Secured on the side of the switch by means

of the bolts 9, 9, is a box 18 having an open upper side, this box having a removable cover 19, and on the lower face of the cover 19 is a projection or lug 20 which extends 5 downwardly within the box and engages the end or head of the bolt or pin 17 so as to prevent lengthwise movement thereof in the holes 15, 16. A hole 21 in the side of the box 18 (see Fig. 2) enables the pin 17 to be 10 put into place and to be removed, the cover 19 first being removed to enable the pin to be put into and removed from its operative position without interference by the lug 20 on the lid or cover 19.

15 The advantages of my invention, which will be appreciated by those skilled in the art, arise from the novel means employed in fastening the swinging switch tongue in operative position within the pocket of the 20 switch body.

Many modifications may be made in the details of the switch structure without departing from my invention as defined in the appended claims.

25 I claim:

1. In a tongue switch, the combination with the switch body, of a swinging tongue pivotally mounted on said body, said tongue having a lug on the under side thereof 30 of, and a pin extending through registering openings in said lug and switch body, said pin being located intermediate the heel and point of the switch tongue, and the ends of the opening in said lug being flared to prevent lifting movement of the tongue relative to the switch body without interference with sidewise swinging movements of the tongue.

2. In a tongue switch, the combination 40 with the switch body of a swinging tongue pivotally mounted on said body, said tongue having a lug on the under side thereof, and a pin extending through registering openings in said lug and switch body, said pin 45 being located intermediate the heel and

point of the switch tongue, and the ends of the opening in said lug being flared to prevent lifting movement of the tongue relative to the switch body without interfering with sidewise swinging movements of the tongue, and means adapted to engage said pin for preventing displacement thereof relative to the switch body. 50

3. In a tongue switch, the combination with the switch body of a swinging tongue 55 pivotally mounted on said body, said tongue having a lug on the lower face thereof, and a pin extending through registering openings in said lug and switch body, said pin being located intermediate the heel and 60 point of the switch tongue, and the ends of the opening in said lug being flared to prevent lifting movement of the tongue relative to the body without interfering with sidewise swinging movements of the tongue, a 65 box on the side of the switch into which said pin extends, and means in said box engaging the end of said pin to prevent lengthwise movement thereof.

4. In a tongue switch, the combination 70 with the switch body of a swinging tongue pivotally mounted on said body, said tongue having a lug on the lower face thereof, and a pin extending through registering openings in said lug and switch body, said pin 75 being located intermediate the heel and point of the switch tongue, and the ends of the opening in said lug being flared to prevent lifting movement of the tongue relative to the body without interfering with sidewise swinging movements of the tongue, a 80 box on the side of the switch into which said pin extends, and a removable cover on said box, said cover having a projection adapted to engage with the end of the pin and prevent displacement thereof when the cover is 85 on said box.

In testimony whereof I have hereunto set my hand.

HENRY C. STIFF.
